CALL TRANSMITTER

Ralph Crocker, Swampscott, Mass.

Application October 17, 1941, Serial No. 415,336

7 Claims. (Cl. 179—90)

The present invention relates to call transmitters and more particularly to units for operating the finger wheels of telephone call transmitters.

It is an object of the present invention to provide a call transmitter of the key controlled type which is of improved construction and arrangement and which is thoroughly reliable in operation.

Another object of the invention is to provide a unit for operating the finger wheel of a telephone call transmitter which may be readily attached to the associated telephone set.

The invention, both as to its organization and method of operation, together with further objects and advantages thereof, will best be understood by reference to the following specification taken in connection with the accompanying drawing, in which Figure 1 is a side elevational view of a telephone set supporting a call transmitter embodying the present invention; Fig. 2 is a face view of the dial plate of the call transmitter; Fig. 3 is an enlarged side elevational view of one of the digit keys carried by the dial plate shown in Fig. 2, illustrating the operated position thereof; and Fig. 4 is an enlarged side elevational view of the digit key shown in Fig. 3, illustrating the released position thereof.

Referring now more particularly to the drawing, there is illustrated a conventional telephone set 10 of the desk type carrying a conventional call transmitter 11 on the front of the base or pedestal thereof, the call transmitter 11 comprising a casing 12, housing the usual impulse transmitting mechanism, and a finger wheel 13 secured to a rotatable arbor 14 extending into the casing 12 and forming a part of the impulse transmitting mechanism. Also, there is illustrated a unit 20 embodying the present invention which operates the finger wheel 13 of the call transmitter 11.

The unit 20 comprises a supporting standard 21 which is detachably secured to the telephone set 10 just above the pedestal and just below the cradle thereof by a clamping arrangement including two screws 22. The standard 21 supports an electric motor 22 disposed directly in front of and in spaced relation with respect to the finger wheel 13 of the call transmitter 11. Preferably, the electric motor 22 is of the single phase, constant speed, synchronous type of conventional construction and arrangement, and is provided with an operating circuit including a source of single phase alternating current of commercial frequency, not shown, and a control switch 23 of the snap action type. More particularly, the electric motor 22 comprises a casing 24, housing the

usual motor elements and speed reduction gearing, not shown, and an operating shaft 25 which projects through the casing 24. The casing 24 of the electric motor 22 is secured to the standard 21 by an arrangement comprising a screw 26 and a plate 27 directly carried by the casing 24.

Also, the unit 20 comprises a substantially U-shaped bracket member 28 provided with two substantially parallel spaced-apart arms 29 and 30. 10 The arm 29 of the bracket 28 is secured directly to the finger wheel 13 and the arbor 14 of the call transmitter 11. More particularly, the lower surface of the arm 29 carries two projections 31 which are received in two of the finger openings provided in the finger wheel 13 of the call transmitter 11. Also, the arm 29 has an opening formed therein which receives the outer end of the arbor 14 of the call transmitter 11, a nut 32 being threaded on the outer end of the arbor 14 15 in order to retain the arm 29 securely clamped in its adjusted position with respect to the finger wheel 13 and the arbor 14 of the call transmitter 11.

The arm 30 of the bracket 28 carries a dial plate or disk 33 arranged above and in spaced relation with respect to the casing 24 of the electric motor 22, the dial plate 33 being secured to the outer surface of the arm 30 by an arrangement comprising a screw 34. The outer end of the operating shaft 25 of the electric motor 22 25 has secured thereto a gear 35 which is arranged below and in spaced relation with respect to the dial plate 33. The arbor 14 of the call transmitter 11, the operating shaft 25 of the electric motor 22 and the center of the dial plate 33 are arranged in alignment along a common center line, for a purpose more fully explained hereinafter.

The dial plate 33 has ten circular holes 34 30 formed therein adjacent the periphery thereof, the holes 34 being equally spaced apart about a major portion of the circumference of the dial plate 33 and disposed in an annular row. Adjacent each of the holes 34 and disposed inwardly 35 with respect thereto, the dial plate 33 carries the usual indicia in the form of the numerals 1, 2, 3, etc., and the letters ABC, DEF, GHI, etc., in accordance with conventional practice. Further, the dial plate 33 carries ten digit keys 1K to 0K, 40 inclusive, which respectively cooperate with the ten holes 34 formed therein.

Preferably, each of the digit keys 1K, etc., is of conventional rocking-bar over-center toggle construction. For example, the digit key 1K 45 comprises a rocking bar 36 pivotally mounted on

a cotter key 37 supported in two aligned openings respectively formed in two substantially L-shaped supports 38, the two supports 38 being disposed on opposite sides of the hole 34 formed in the dial plate 33 and suitably secured to the outer surface thereof. Further, the digit key 1K comprises a toggle arm 39 pivotally mounted at the upper end thereof and adapted to oscillate about the vertical center line of its pivot in accordance with conventional practice. Further, the rocking bar 36 comprises an operating projection or tab 40 disposed on one end thereof and a releasing projection or tab 41 disposed on the opposite end thereof.

It will be readily understood that when the elevated operating tab 40 is depressed the rocking bar 36 is rotated in a clockwise direction about the cotter key 37 in order to cause the releasing tab 41 to be elevated and the toggle arm 39 to be oscillated about its pivot toward the gear 35, the elements mentioned being moved from the positions shown in Fig. 4 to the positions shown in Fig. 3 with a snap action; on the other hand, when the elevated releasing tab 41 is depressed the rocking bar 36 is rotated in a counterclockwise direction about the cotter key 37 in order to cause the operating tab 40 to be elevated and the toggle arm 39 to be oscillated about its pivot away from the gear 35, the elements mentioned being moved from the positions shown in Fig. 3 to the positions shown in Fig. 4 with a snap action. The lower end of the toggle arm 39 carries a projection 42 which is adapted to engage and disengage the teeth provided on the periphery of the gear 35 when the toggle arm 39 occupies its respective positions shown in Figs. 3 and 4. Accordingly, it will be understood that when the elevated operating tab 40 of any one of the digit keys 1K, etc., is depressed the releasing tab 41 thereof is elevated and the toggle arm 39 thereof is oscillated about its pivot in order to move the projection 42 into engagement with the teeth provided about the periphery of the gear 35, whereby the dial plate 33 is clutched to the gear 35; on the other hand, when the elevated releasing tab 41 of any one of the digit keys 1K, etc., is depressed the operating tab 40 thereof is elevated and the toggle arm 39 thereof is oscillated about its pivot in order to move the projection 42 out of engagement with the teeth provided about the periphery of the gear 35, whereby the dial plate 33 is declutched from the gear 35.

Finally, the unit 20 comprises a substantially U-shaped releasing element 43 provided with two substantially parallel spaced-apart arms 44 and 45. The arm 44 of the releasing element 43 is disposed below the dial plate 33 and secured to the standard 21 by the screw 26; while the arm 45 of the releasing element 43 is disposed above the dial plate 33 and provided with an upwardly turned outer end 46 overhanging the annular row of digit keys 1K, etc. More particularly, the upwardly turned outer end 46 provided on the arm 45 of the releasing element 43 overhangs the annular row of releasing tabs 41 carried by the rocking bars 36 of the digit keys 1K, etc. The arm 45 of the releasing element 43 is spaced above the upper surface of the dial plate 33 a distance sufficient to permit the depressed releasing tabs 41 carried by the rocking bars 36 of the various digit keys 1K, etc., to pass thereunder, incident to rotation of the dial plate 33, without engagement therewith; however, this spacing of the arm 45 of the releasing element 43 above the

upper surface of the dial plate 33 is such that an elevated releasing tab 41 carried by a rocking bar 36 of any one of the digit keys 1K, etc., will engage the upwardly turned outer end 46 of the arm 45, whereby the elevated releasing tab 41 carried by the rocking bar 36 of the digit key 1K, etc., is depressed.

The finger wheel 13 of the call transmitter 11 has a normal position and is adapted to be variably rotated therefrom in a clockwise direction, as viewed in Figs. 1 and 2, in accordance with the different digits to be transmitted. Subsequently, when the finger wheel 13 of the call transmitter 11 is released it is rotated in a counterclockwise direction, as viewed in Figs. 1 and 2, back into its normal position by the usual spring motor; whereby the impulse transmitting mechanism housed in the casing 12 of the call transmitter 11 transmits a corresponding number of impulses in accordance with conventional practice. The dial plate 33 has a normal position and is variably rotatable away from its normal position in the clockwise direction, as viewed in Figs. 1 and 2, in accordance with the different digits to be transmitted in view of the fact that the dial plate 33 is directly and rigidly secured to the finger wheel 13 of the call transmitter 11 by the bracket 28. When the control switch 23 is actuated to close the operating circuit of the electric motor 22 the motor 22 operates in order to cause the operating shaft 25 and consequently the gear 35 to be rotated continuously in the clockwise direction, as viewed in Figs. 1 and 2; this operation of the electric motor 22 and the consequent rotation of the operating shaft 25 and the gear 35 carried thereby continuing as long as the operating circuit of the electric motor 22 is completed by the actuated position of the control switch 23.

Considering now the operation of the unit 20 in conjunction with the call transmitter 11 to transmit one or more digits from the telephone station provided with the telephone set 10, the operator first actuates the control switch 23 in order to initiate operation of the electric motor 22 and the consequent rotation of the operating shaft 25 thereof and the gear 35 carried thereby, in the clockwise direction, as viewed in Figs. 1 and 2. The operator then effects the transmission of the first digit by depressing the elevated operating tab 40 carried by the rocking bar 36 of the appropriate digit key 1K, etc. When the elevated operating tab 40 carried by the rocking bar 36 of the appropriate digit key 1K, etc., is thus depressed the releasing tab 41 carried by the rocking bar 36 thereof is elevated and the toggle arm 39 thereof is oscillated about its pivot in order to move the associated projection 42 into engagement with the teeth of the constantly rotating gear 35, whereby the dial plate 33 is clutched to the gear 35 by the appropriate digit key 1K, etc., mentioned. At this time, the dial plate 33, being clutched to the gear 35, is rotated in the clockwise direction therewith away from its normal position. Also, the finger wheel 13 of the call transmitter 11 is rotated in a clockwise direction away from its normal position, together with the dial plate 33, due to the rigid connection comprising the bracket 28 extending between the finger wheel 13 and the dial plate 33.

The dial plate 33 is rotated, in the clockwise direction, a predetermined distance away from its normal position corresponding to the position of the operated digit key 1K, etc., with respect to the other digit keys in the annular row, where-

upon the elevated releasing tab 41 carried by the rocking bar 36 of the operated digit key 1K, etc., engages the upwardly turned outer end 46 carried by the arm 45 of the releasing element 43 and is depressed, as previously explained. When the elevated releasing tab 41 carried by the rocking bar 36 of the operated digit key 1K, etc., is thus depressed the operating tab 40 carried by the rocking bar 36 thereof is elevated and the toggle arm 39 thereof is oscillated about its pivot 10 in order to move the projection 42 out of engagement with the teeth provided on the periphery of the gear 35. Hence, the dial plate 33 is declutched from the gear 35 in order to permit free rotation of the continuously rotating gear 35 with respect to the dial plate 33 at this time. When the dial plate 33 and the finger wheel 13 of the call transmitter 11 are thus rotated in the clockwise direction, as viewed in Figs. 1 and 2, the mechanism housed in the casing 12 of the call transmitter 11 is set to transmit a corresponding digit and the spring motor housed therein is wound. At this time the spring motor housed in the casing 12 of the call transmitter 11 returns the finger wheel 13 thereof and consequently the dial plate 33 in the counterclockwise direction, as viewed in Figs. 1 and 2, back into their normal positions. When the finger wheel 13 of the call transmitter 11 is returned in the counterclockwise direction back into its normal position the impulse transmitting mechanism housed in the casing 12 thereof operates to transmit the corresponding digit. At this time the elements of the call transmitter 11 and the unit 20 occupy their normal positions; accordingly, another one of the digit keys 1K, etc., may be operated in accordance with the second digit to be transmitted from the telephone station.

In view of the foregoing explanation of the mode of operation of the unit 20 in conjunction with the call transmitter 11, it will be readily understood that each time one of the digit keys 1K, etc., carried by the dial plate 33 is operated the unit 20 operates in order to effect operation of the call transmitter 11 to transmit the corresponding digit; and that, by repeatedly operating the various digit keys 1K, etc., carried by the dial plate 33, the unit 20 may be selectively controlled to govern the operation of the call transmitter 11 to transmit a series of digits comprising the directory number of a called telephone station.

While one embodiment of the invention has been disclosed, it will be understood that various modifications may be made therein which are within the true spirit and scope of the invention.

What is claimed is:

1. A unit for operating the finger wheel of a call transmitter supported by a telephone set; said unit comprising a support adapted to be secured to the telephone set, a member adapted to be secured to the finger wheel of the call transmitter, a set of digit keys movable with said member, a motor, and means selectively controllable by said digit keys for imparting variable rotation to said member from said motor, whereby the finger wheel of the call transmitter is selectively rotated in accordance with the operation of said digit keys in order to cause the call transmitter to transmit corresponding digits.

2. A unit for operating the finger wheel of a call transmitter; said unit comprising a member adapted to be secured to the finger wheel of the call transmitter, a set of digit keys movable with said member, a motor, and means selectively

controllable by said digit keys for imparting variable rotation to said member from said motor, whereby the finger wheel of the call transmitter is selectively rotated in accordance with the operation of said digit keys in order to cause the call transmitter to transmit corresponding digits.

5. In a call transmitter, a first rotatably mounted member biased to a normal position and variably rotatable away from its normal position in accordance with different digits to be transmitted, a second rotatably mounted member, a motor for rotating said second member, a set of manually operable digit keys, means responsive to the operation of any one of said digit keys for restraining operated said one digit key and for clutching said first member to said second member together for continuous rotation, whereby said first member is rotated away from its normal position, means responsive to the rotation of said first member away from its normal position an amount corresponding to said one digit key for releasing said one digit key, means responsive to the release of said one digit key for declutching said first member from said second member, 20 whereby said first member is rotated back to its normal position, and digit transmitting means operated by the rotation of said first member for transmitting a digit corresponding to said one digit key.

30. 4. In a call transmitter, a first rotatably mounted member biased to a normal position and variably rotatable away from its normal position in accordance with different digits to be transmitted, a second rotatably mounted member, a motor for rotating said second member, a set of manually operable digit keys disposed in a row and carried by said first member, means responsive to the operation of any one of said digit keys for restraining operated said one digit key and 35 for clutching said first member to said second member, whereby said first member is rotated away from its normal position, a release element, said digit keys in the row being brought successively adjacent to said release element as said first member is rotated away from its normal position, means including said release element for releasing said one digit key when it is brought adjacent thereto, means responsive to the release of said one digit key for declutching said first member from said second member, whereby said first member is rotated back to its normal position, and digit transmitting means operated by the rotation of said first member for transmitting a digit corresponding to said one digit key.

45. 5. In a call transmitter, a first rotatably mounted member biased to a normal position and variably rotatable away from its normal position in accordance with different digits to be transmitted, a second rotatably mounted member, a motor for rotating said second member, a set of manually operable digit keys disposed in a row and carried by said first member, each of said digit keys being of the rocking-bar type including an operating projection and a releasing projection, means controlled when the operating projection 50 of any one of said digit keys is depressed for restraining depressed the operating projection thereof and for elevating the releasing projection thereof, means responsive to the depression of the operating projection of said one digit key for clutching said first member to said second member, whereby said first member is rotated away from its normal position, a release element, the release projections of said digit keys in the row being brought successively adjacent to said re-

lease element as said first member is rotated away from its normal position, whereby the elevated releasing projection of said one digit key is brought into engagement with said release element and depressed thereby, means responsive to the depression of the releasing projection of said one digit key for elevating the operating projection thereof, means responsive to the elevation of the operating projection of said one digit key for declutching said first member from said second member, whereby said first member is rotated back to its normal position, and digit transmitting means operated by the rotation of said first member for transmitting a digit corresponding to said one digit key.

6. A unit for operating the finger wheel of a call transmitter supported by a telephone set; said unit comprising a support adapted to be secured to the telephone set, a member adapted to be secured to the finger wheel of the call transmitter to rotate therewith, a set of digit

keys mounted in an annular series to rotate with said member, a motor, a rotary member adapted to be rotated continuously by said motor, and means selectively controllable by said digit keys for selectively forming driving connections between said members to cause variable degrees of rotation of said first-named member depending upon the position of the operated digit key.

7. In a call transmitter, a finger wheel biased to a normal position and variably rotatable away from that position in accordance with different digits to be transmitted, a second rotatably mounted member, a motor for rotating said last-named member, a set of manually operated digit keys movable with said finger wheel, means responsive to the operation of any one of said digit keys for establishing a driving connection to cause said finger wheel to rotate to an extent determined by the position of the operated digit key.

RALPH CROCKER.
